RELEASING DEVICE

John H. Derby, Scarsdale, N. Y., and Thomas G. Collings, North Plainfield, N. J.

Application August 5, 1950, Serial No. 177,877

2 Claims. (Cl. 74—2)

1

This invention relates to devices known to the trade as "release boxes." Release boxes, to improvements in which the invention is particularly directed, are devices which can be operated from a distance to release something held against operation or movement, such, for example, as fire doors, fire dampers, theatre fire curtains, dip tank covers, valves which control the release of liquids or gases used for fire extinguishing, etc. Although release boxes find their most important field of utility in the fire prevention art they are also useful for other purposes where it is desirable that the operation or movement of some device held against operation or movement be controlled from a distance.

Release boxes as heretofore constructed, see for example U. S. Letters Patent to John H. Derby No. 1,187,135, granted June 13, 1916, and U. S. Letters Patent to T. G. Collings, No. 2,174,969, granted October 3, 1939, have usually comprised a series of power-multiplying bellcrank levers and a trippable detent comprising a lever having a trip arm engageable with the last of the series of bellcranks, this trippable detent being normally urged toward its holding position by a spring and being arranged to be tripped by an electromagnet energized by the closing of a circuit in which its coils are included.

Unless the electrical parts of release boxes just described are in what are known as "supervisory circuits," that is, closed circuits including "trouble" alarms and through which a small amount of current, below operating level, flows constantly, the release boxes being operated by a sharp rise in the flow of current, there is some danger that the operating circuit may be broken so that when the operating switch is closed the detent tripping magnet will not be energized. One of the objects of the present invention is to provide a simpler and less expensive release box which will have all of the advantages of release boxes located in supervisory circuits, so far as warning of its inoperativeness is concerned, the release box of the present invention operating by the breaking of a normally closed circuit through the release box magnet rather than by the closing of a circuit therethrough or by an increase in the flow of current therethrough as in the prior devices above referred to.

With this and other objects in view the invention aims to provide a simple but surely operating release mechanism in which the parts to be held against release by the release box are only so held so long as a current flows through the detent retaining electromagnet of the release box.

An important feature of the invention is the provision of simple means for resetting the release box after it has operated, without the necessity for opening the box to get at the trip mechanism on the inside thereof.

Another important feature of the invention is the construction of the parts so that they are protected from dirt, adverse atmospheric conditions, corrosion and other things that might interfere with their operation when operation is desired. Still another important feature of the invention, in a release box in which a detent lever, which is arranged to be held in holding relation to the trip lever of the release box by an electromagnet so long as the magnet is energized, is constantly spring urged toward releasing position, is the construction of the interengaging parts of the detent lever and the load holding and releasing or trip lever so that the load upon the trip or release lever will tend to force the two levers into separated relation, when the circuit is broken, even if the spring which normally urges the detent lever out of engagement with the load holding and releasing or trip lever has become more or less inoperative.

Other objects, important features and advantages of the invention, to which reference has not hereinabove specifically been made, will appear hereinafter when the following specification and claims are considered in connection with the accompanying drawings, in which

Figure 1 is a front elevation, with parts broken away to permit showing thereof on a larger scale, of a release box embodying the present invention in operative retaining relation to an ordinary gravity-closing fire door;

Figure 2 is a front elevation of the interior mechanism of the release box of Figure 1, the cover being shown as removed from the box and the trip lever and detent lever being shown in their operative load-retaining position;

Figure 3 is a view similar to Figure 2, showing the box after it has been tripped by the breaking of the circuit through the detent-holding electromagnet;

Figure 4 is a section on the line 4—4 of Figure 2 looking in the direction of the arrows;

Figure 5 is a section on the line 5—5 of Figure 2 looking in the direction of the arrows;

Figure 6 is a section on the line 6—6 of Figure 2 looking in the direction of the arrows, and

Figure 7 is an enlarged detail side elevation of the engaging parts of the detent lever and the trip or load holding and release lever showing the angular relations of the engaging faces to the di-

rection of the force acting thereon, whereby the tripping movement is facilitated.

In the illustrative embodiment of the invention the main elements of the load holding and release mechanism are enclosed within a box-like casing 2 having top and bottom flanges 4 and 6 through which retaining bolts or screws 8 may pass to connect the box to the wall or other stationary part adjacent to the firedoor or other movable part to be held against movement. The box or casing 2 is provided with a cover 10 to protect the internal mechanism against dirt or corrosive fumes, vapors or gases, the cover being removably secured to the box by screws 12 at its corners.

A fulcrum shaft 14, having its bearings in a thickened part 16 of the wall of the casing, has fixed upon the part thereof which projects through the side wall to the outside a short load holding and releasing or trip arm 18 and has fixed upon its end which projects into the casing a long arm 20, the structure thus described constituting a power multiplying lever by which a relatively large pull upon the short arm 18, say 50 pounds, exerted by a hook 22 connected by a strap 24 to the firedoor 26, or other part to be held in its open condition or to be held against movement, may be resisted by the exertion of a relatively small retaining force upon the end of the arm 20.

The retaining means herein shown for resisting the tendency of the pull upon the arm 18 to rock the load holding and releasing or trip lever about the axis of the shaft 14 toward its release position comprise a detent lever 28 having a pawl-like end or dog 30 adapted to hook over the end of the long arm 20 of the load holding and releasing or trip lever and thus to hold the lever in the position shown in Figure 2 against turning under the pull of the load on the load hook 22.

As shown particularly in Figure 7 the pawl-like end or dog 30 of the detent lever 28 has its under face inclined to the direction of the force exerted upon it by the arm 20 at such an angle, and the part of the end of the lever arm 20 which engages the under face of the part 30 is also so correspondingly inclined to this direction of the said force, that, in the event of a failure of the spring 32, which ordinarily constantly urges the detent lever 28 to swing in a counter-clockwise direction in Figure 2 about its pivot 34, the pressure of these two engaging faces on each other will produce a component of force tending to move the pawl-like end 30 of the detent lever 28 out of its retaining relation to the end of the arm 20 and thus effect the release of the arm 20 and of the firedoor 26 or other part held against movement by the trip arm 18.

As hereinabove pointed out, the detent lever 28 is held in its holding relation to the arm 20 of the trip lever by an electromagnet having coils 36 and 38 about the two legs of a laminated horseshoe-shaped core 40, the horseshoe-shaped core being supported upon a bracket 42 attached to the wall of the casing 2. The core 40 in turn sustains the coils 36 and 38. The two poles of the electromagnet, constituted by the ends of the core legs, when energized act upon an armature 44 connected to the detent lever 28 and thus, by pulling the detent lever toward the poles of the electromagnet, maintain the pawl-like end 30 of the detent lever in retaining relation to the long arm 20 of the load holding and release or trip lever. An adjustable stop 46, held in its adjusted

relation by a lock nut 48, limits the movement of the detent lever 28 out of its retaining relation to the arm 20.

The wires 50 and 52, through which the energizing current for the electromagnet coils is brought into the release box, enter the box through an opening 54 in a boss 56 on the bottom of said box and are connected to binding screws 56 and 58. Other binding screws 60 and 62 in contact plates connected respectively to the binding screws 56 and 58 are provided for the connection of the coil terminals.

A stop screw 64 screwed into the wall of the casing 2 preferably limits the upward swing of the arm 20 of the trip lever. If desired the arm 20 may be provided with a rounded recess 66 to fit the shank of the screw 64.

To facilitate resetting of the release box after it has been tripped the end of the arm 20 of the trip lever is provided with a bevel 68 adapted to cooperate with the corresponding bevel 70 on the top of the pawl-like end 30 of the detent lever 28 to force the detent lever 28 away from the poles of the magnet in the event that the electromagnet has become energized before the box has been reset. The trip lever may be rocked for this purpose by means of its short arm 18. However, ordinarily the long arm 20 of the trip lever will gravitate back into its set relation, if there be no load on the short arm 18, by reason of its greater length, this movement of the lever being limited by a second stop screw 72. Energization of the electromagnet coils 36 and 38 will then move the detent lever 28 into retaining relation to the arm 20.

Referring again to Figure 7 of the drawings, it has been found in practice that if the meeting faces of the pawl-like end 30 of the detent lever 28 and the end of the lever arm 20 be inclined to the direction of force at an angle of 6.5° plus or minus .5°, the desired releasing component of force will be provided, especially if the engaging faces of the pawl-like end 30 and the arm 20 be suitably plated with some protective metal coating such, for example, as chromium or cadmium.

Washers 74 of Bakelite or some suitable similar material on each side of the hub of the detent lever 28 help maintain this lever in good working condition. It will be seen that by employing a power multiplying lever in which the arm 20 inside the casing is several times the length of the load-retaining and releasing arm 18 and having the detent engage the long arm 20 at its extreme end, the amount of force required to hold the load against release is comparatively small. It will further be seen that by arranging the detent lever in the manner shown so that it lies normally at right angles to the long arm 20 and having the armature located as shown, the pull upon the armature required to maintain the detent in its operative load-retaining position is comparatively small thus permitting low wound coils to be used in the electromagnets and thereby increasing the number of releases which can be connected in series. This reduces materially the installation cost where a number of releases are to be used.

What we claim as new is:

1. A release box operable upon the breaking of a closed electric circuit comprising, in combination with a box-like casing, a lever having a fulcrum shaft extending through a wall of the casing and having a short load retaining trip arm fixed to said shaft on the outside of the casing and a power multiplying long arm fixed to said shaft on the inside of said casing, a detent lever

having a pawl-like end adapted to be brought into retaining relation to the upper face of the free end of said long arm, said detent lever being arranged to be brought into but spring-urged out of holding relation to said long arm, an armature on said detent lever and an electromagnet acting on said armature when energized to hold said detent lever in holding relation to said long lever arm, the engaging faces of the pawl-like end of the detent lever and said long arm lying at such an angle to the radius of swing of said long arm that a component of the force transmitted from the load to be released through said long arm to said pawl-like end of said detent lever at least counterbalances the friction between said engaging faces, thereby facilitating the release of said long arm by said detent lever.

2. A release box according to claim 1 in which the detent lever is mounted to swing through an arc into and out of its operative relation to

the long arm of the load holding and release lever which is substantially normal to the arc of movement of said long arm as its starts its release movement, the engaging faces of the pawl-like end of said detent lever and the long arm of the load holding and release lever being inclined slightly to a tangent to the arc of swing of the detent lever.
